UNITED STATES PATENT OFFICE.

PETER HERDIC FULLER, OF DOBBS FERRY, NEW YORK.

DESIGN FOR A LOUD-SPEAKER RESONATOR OR THE LIKE.

Application filed July 9, 1927. Serial No. 22,716. Term of patent 14 years.

To all whom it may concern:

Be it known that I, PETER H. FULLER, a citizen of the United States, and a resident of Dobbs Ferry, in the county of Westchester and State of New York, have invented a new, original, and ornamental Design for a Loud-Speaker Resonator or the like, of which the following is a specification, refer-

ence being had to the accompanying drawing, forming part thereof.

The figure is a perspective view of a loud speaker resonator showing my new design.

I claim:

The ornamental design for a loud speaker resonator or the like, as shown.

PETER HERDIC FULLER.
